UNITED STATES PATENT OFFICE.

GIOVANNI EMANUELE ELIA, OF WESTMINSTER, LONDON, ENGLAND, ASSIGNOR TO
VICKERS LIMITED, OF WESTMINSTER, ENGLAND.

SUBMARINE MINE.

1,226,197.

Specification of Letters Patent. Patented May 15, 1917.

Application filed February 23, 1917. Serial No. 150,435.

To whom it may concern:

Be it known that I, GIOVANNI EMANUELE ELIA, a subject of the King of Italy, residing at Vickers House, Broadway, Westminster, in the county of London, England, have invented certain new and useful Improvements in or Relating to Submarine Mines, of which the following is a specification.

This invention relates to the firing gear of submarine mines.

According to the invention the firing gear is provided with a retaining or safety device arranged within the mine casing and connected to a tension member which is placed under tension prior to the launching of the mine to hold the said device in its retaining or safety position and which is also arranged within the mine casing. The sea water and substances suspended therein are thus prevented from gaining access to the said device and the tension member. The said tension member is preferably in the form of a cable which may be supported upon a number of loose pulleys arranged in two horizontal rows on the inner surface 25 of the mine casing; one of these rows may be situated at or near the upper part of the mine casing and the other at or near the portion of the mine having the largest diameter, the tension cable being passed over each pulley in the upper row and under each pulley in the lower row, so that the said cable is stretched in an undulating or sinuous manner along the inner surface of 30 the mine casing. When a ship strikes the mine the tension on the said tension cable is relieved by the explosion of one or more of a number of small powder charges arranged around the mine contiguous to some or all of the pulleys, thus permitting the retaining device to be displaced and the mine fired. In an alternative arrangement I provide means whereby the tension on the internally arranged tension member is relieved mechanically when a ship strikes the mine. For this purpose when the tension member is in the form of a cable passing sinuously over a number of pulleys arranged within the mine casing, the pins on which 45 the pulleys are loosely mounted are subject to the influence of springs which tend to move the pins inwardly independently of the pulleys so as to liberate the latter and thus relieve the tension on the cable. This 50 movement of the pins is prevented by de-

vices arranged on the outside of the mine casing, these devices being of such a character that when the mine is struck by a ship they will be displaced to permit the pins to be disengaged from the pulleys by 60 their springs. The said means for mechanically relieving the tension on the cable when a ship strikes the mine may, in another construction comprise a spring controlled member which is normally housed 65 within the mine casing and is held in its inward or housed position by a plug of sal-ammoniac or other soluble salt so that after the mine has been launched and has been in the water for a predetermined length of 70 time, the plug of salt will be dissolved and the spring controlled member will be caused by its spring to protrude from the surface of the mine casing.

In order that the said invention may be 75 clearly understood, and readily carried into effect, the same will be described more fully with reference to the accompanying drawings, in which:

Figure 1 is a side elevation of a mine provided with a constructional form of the 80 improvements.

Fig. 2 is a vertical section showing one constructional form of the means employed for relieving the tension on the tension 85 member.

Fig. 3 is a vertical section showing the preferred form of the aforesaid retaining or safety device in its retaining or safety position.

Fig. 4 is a section taken approximately on the line 1, 1 of Fig. 3.

Fig. 5 is a view similar to Fig. 3 but showing the retaining or safety device in its releasing or firing position, the mine being 95 on the point of being fired.

Fig. 6 is a section taken approximately on the line 2, 2 of Fig. 5.

Fig. 7 is a view similar to Fig. 5 but showing the parts in the position they occupy 100 when the striker of the firing gear has been impelled by its spring to fire the mine.

Fig. 8 is a section of a constructional form of the means employed for mechanically relieving the tension on the tension member, 115 and

Fig. 9 is a view similar to Fig. 8 showing another constructional form of the means for mechanically relieving the tension on the tension member.

A is the mine casing. B is the tension cable and b, b are the pulleys around which the said cable is stretched in a sinuous manner. C is the retaining or safety device to which the tension cable B is connected. D 5 is the striker head, D' the striker stem and D² the anchor cable connecting the said stem to the anchor of the mine.

In the example shown the retaining or 10 safety device C is in the form of a disk or plate controlled by a spring C' which exerts a pull on the disk C in the opposite direction to the pull of the tension cable B. The disk is mounted so as to be capable of 15 angular movement about the axis of the striker stem D', and is so formed in relation to a collar d' on the striker stem D' that the said disk and collar constitute a bayonet joint so that when the disk C is displaced by the spring C' into the position shown by 20 Fig. 6 when the tension on the tension cable B is relieved, the disk will become liberated from the collar d'; the upward pull or buoyancy of the mine will then cause the mine to be fired as is well understood. To 25 prevent the collar d' from becoming angularly displaced from the disk, the mine casing is provided with a stud a engaging in a hole d² in a flange on the said collar. The 30 striker head D is detachably connected to the striker stem D' in such a manner that the head becomes liberated from the stem after the mine has risen under the influence of its buoyancy a predetermined extent in relation to the striker stem. For 35 this purpose, as is well understood, the striker head may be connected to the striker stem by one or more shear pins or by pins which move with the head and the stem into 40 such a position that they are automatically displaced to disconnect the head from the stem.

In the example shown by Figs. 1 and 2 45 the means for relieving the tension on the tension cable B comprise a number of wheels E each of which is connected to a sleeve E' carrying one element e' of a bayonet joint connection, the other element e of which is constituted by part of a spring controlled 50 striker E² slidably mounted within a tube e² containing a percussion cap e³ and a powder charge E⁴. In order to prevent sea water from entering between the sleeve E' and the tube e², a rubber or other 55 suitable collar e⁴ is connected to each of these parts. The end of the sleeve contiguous to this rubber collar may be cut away to form an inclined surface upon which the said collar bears under the pressure of the 60 sea water. A suitable catch E⁵ held by a sal-ammoniac plug e⁵, in position to engage with the sleeve E' is provided for preventing angular movement of the sleeve until a certain time has elapsed after launching 65 the mine. This catch is controlled by a

spring, preferably a torsion spring disposed around the pivot pin e⁶ of the said catch. Several of these tension relieving apparatus are situated around the mine near the upper part thereof with the sleeves E' vertically 70 disposed; the wheels E on the upper ends thereof are of such diameter that their outer portions extend beyond the portion of the mine casing having the greatest diameter. In this manner the wheels will be angularly 75 displaced and the powder charges exploded by the contact of the side of a moving ship with the wheels. Each of these powder charges is situated contiguous to one of the upper pulleys b so that the force of the explosion breaks the pulleys away from the mine casing and may also break the tension cable B. In either case the tension on the said cable is relieved to permit the spring C' to displace the disk C and liberate the 80 firing gear in the manner set forth above. 85

In the example shown by Fig. 8, the means for relieving the tension on the tension cable B comprise a block F connected to the outer projecting end of the movable pulley pin B' by a breakable screw f. When a ship strikes the mine, the consequent rotation of the latter brings the block F forcibly against the side of the ship and causes the breakable screw f to be fractured. The pin B' is then free to move inward under the influence of its spring b' until it becomes clear of the pulley B. The latter is then unsupported and the tension on the cable relieved. The outer end of the pin 100 passes through a suitable watertight packing F' carried by the mine casing. The block F is normally protected by a cover plate F² which is held in its closed position prior to the launching of the mine by 105 a suitable device comprising a sal-ammoniac or other soluble salt plug f². This device comprises a retaining pin F³ carried by a bracket on the mine casing and engaging 110 with part of the plate F². The retaining pin F³ is held in its engaging position against the opposition of a spring f³ by the said plug f² of sal-ammoniac or other soluble salt. The plate F² is pivoted and is moved about its pivot pin f⁴ to uncover the 115 aforesaid block, by a helical torsion spring f⁵ interposed between the pivot pin and the plate.

In Fig. 9, G is the aforesaid spring controlled member which is in the form of a 120 plunger normally housed as shown within the mine casing A. g is the plug of sal-ammoniac or other soluble salt for holding the said plunger in its housed position prior to the launching of the mine. This plug is interposed between a collar on the plunger G and a number of hook shaped members (of which one is indicated by g^x) detachably connected to a sleeve G' within which the plunger G is slidably mounted. The plun- 130

ger G is hollow and contains a helical compression spring G^x which serves, when the plug g has dissolved, to move the plunger to a position in which it protrudes from the 5 surface of the mine casing. The said sleeve G' carries a spring controlled catch or pawl g' having a nose g'^x adapted to engage in a hole g² in the plunger G when the latter reaches its fully protruding position. The 10 nose of this catch is disposed in a keyway G² formed in the plunger and the said nose is thereby guided into the hole. The inner end of the sleeve is connected by a brittle steel pin f to a rod g³ carrying a collar G³ which engages with a pivoted hook G⁴ upon which the pulley b carrying the tension cable B is mounted. This collar is controlled by a 15 spring g⁴ so that when the aforesaid brittle pin f is broken by the impact of a ship with the protruding plunger the said spring displaces the collar into a position to release the aforesaid hook; the pulley b is therefore no longer supported and the tension on the 20 tension cable is relieved so that the mine is free to be fired by the upward movement of the mine due to its buoyancy as aforesaid. The plunger G and the sleeve G' are carried within a casing G⁵ the outer portion of which is normally closed by a screw threaded 25 cap g⁵; this cap prior to the launching of the mine prevents water or moisture from coming into contact with the plug g and also protects the plunger against blows that might fracture the aforesaid brittle pin; the 30 said cap is removed when the mine is about to be launched.

What I claim and desire to secure by Letters Patent of the United States is:—

1. Submarine mine firing gear comprising 40 in combination a retaining device for normally holding said gear inoperative, said device being arranged within the mine casing, a tension member arranged within the mine casing and connected to said device, and 45 means for relieving the tension on said member, when a ship strikes the mine, to release said retaining device.

2. A submarine mine comprising the combination of a mine casing, firing gear for the 50 mine, a retaining device located within the casing for holding the firing gear inoperative, a plurality of supports within the casing, a flexible member positioned by the sup-

ports and connected to the retaining device, and means operated by engagement of a 55 ship with the mine for displacing one or more of the supports, so that the flexible member will no longer prevent movement of the retaining device.

3. Submarine mine firing gear comprising 60 in combination a retaining device for normally holding said gear inoperative, said device being arranged within the mine casing, a tension member arranged within the mine casing and connected to said device, 65 and means for mechanically relieving the tension on said member, when a ship strikes the mine, to release said retaining device.

4. Submarine mine firing gear comprising 70 in combination a retaining device for normally holding said gear inoperative, said device being arranged within the mine casing, a tension cable arranged within the mine casing and connected to said device, a pulley by which said cable is supported, said pulley 75 being normally connected to the mine casing and means for disconnecting said pulley from the mine casing when a ship strikes the mine.

5. Submarine mine firing gear comprising 80 in combination a retaining device for normally holding said gear inoperative, said device being arranged within the mine casing, a tension cable arranged within the mine casing and connected to said device, a pulley 85 by which said cable is supported, a spring controlled pin by which said pulley is normally supported on the mine casing and means for liberating said pin when a ship strikes the mine, for enabling the spring of 90 the pin to displace the pin and disconnect the pulley from the mine casing.

6. Submarine mine firing gear comprising 95 in combination a retaining device for normally holding said gear inoperative, said device being arranged within the mine casing, a tension member arranged within the mine casing and connected to said device, means for relieving the tension on said member, when a ship strikes the mine, to release said 100 retaining device, said means comprising a spring controlled member which is held prior to the immersion of the mine in a housed position within the mine casing.

GIOVANNI EMANUELE ELIA.
